UNITED STATES PATENT OFFICE.

RICHARD PAUL HABEL, OF STURGIS, SOUTH DAKOTA.

LAMP.

SPECIFICATION forming part of Letters Patent No. 753,066, dated February 23, 1904.

Application filed November 4, 1902. Serial No. 130,050. (No model.)

To all whom it may concern:

Be it known that I, RICHARD PAUL HABEL, a citizen of the United States, and a resident of Sturgis, in the county of Meade and State of 5 South Dakota, have invented new and useful Improvements in Lamps, of which the following is a full, clear, and exact description.

This invention relates to improvements in gasolene-lamps, the object being to provide a 10 simple means for causing a constant and uniform pressure on the gasolene without the use of pumps, thus resulting in a steady light.

Other objects of the invention will appear in the general description.

15 I will describe a lamp embodying my invention and then point out the novel features in the appended claims.

Reference is to be had to the accompanying drawings, forming a part of this specification, 20 in which similar characters of reference indicate corresponding parts in all the figures.

Figure 1 is an elevation of a lamp embodying my invention. Fig. 2 is a sectional elevation of the reservoir. Fig. 3 is a sectional 25 view of one of the generators employed; and Fig. 4 is a detail view, on an enlarged scale, of a portion of one rod and its wire-netting.

Referring to the drawings, 1 designates the reservoir for gasolene, which may be suspended by means of a hanger 2. On one side of the reservoir near the top is a filling-nipple 3, which is normally closed by a screw-plug 4. When filling the reservoir, however, I employ a funnel 5, which may be screwed 30 into the nipple, and on this funnel is a valve-controlled outlet 6, so that by opening the valve the spilling of the surplus oil in the funnel will be prevented—that is, as the reservoir becomes filled the surplus oil in the 35 funnel will run out through the outlet 6. Movable in the reservoir is a pressure device 40 consisting of a plunger 7. This plunger preferably is made of hard rubber, as such material will not absorb gasolene as iron or similar material might. This plunger is made of a size to fit snugly within the reservoir, but to freely slide therein.

From the plunger a vent-tube 8 extends upward and slides through a stuffing-box 9 in 45 the cover 10 of the reservoir. This tube 8,

as here shown, is connected to a metal thimble 11, secured in the plunger by means of a plate 12. On the outer end of the vent-tube is a valve 13, and also connected to the outer end is a ring 14, designed to be engaged with 55 a hook 15 when the reservoir is to be filled, as will be hereinafter described. Attached to the vent-tube is a cross-head 16, and from the ends of this cross-head rods 17 extend down through openings in guide-arms 18, attached 60 to the cover 10, and on the lower ends of these rods are weights 19. Leading through the bottom of the reservoir is a supply-tube 20, which communicates with branches 21, on the ends of which are curved generator-tubes 22. 65 On the end of each generator-tube is a thimble 24, having a conical outlet 25, which ejects the gas in a spray. The mixed gasolene and air forming the gas passes from the thimble 24 into a burner-tube 26, supporting a burner 27. The inner end of each burner-tube 26 is made in the form of a funnel 28, adjustable on the tube, so as to regulate the space between it and the thimble 24. 70

Arranged in the bend of each generator-tube 75 22 is a netting 29 30, consisting of steel or other similar material, and connected to the netting material 29 is a metal rod 31, which extends through the upper portion of the generator-tube, and connected to the netting 30 80 is a metal rod 32, which extends through the lower portion of said generator-tube. These rods 31 32 are a trifle smaller than the inner diameter of the tube, permitting a small amount of gasolene to pass through the tube. 85 By thus arranging the parts the gasolene in being spread by the rods may be quickly generated into gas.

When it is desired to clean a generator-tube, it may be removed from the casing of the valve 90 23 on the tube 21 and also from the thimble 24, when the rods, with the wire-netting attached, may be drawn out. It will be noted that the feed-tube 20 extends upward above the bottom of the reservoir, so that by this 95 arrangement very little or no sediment will enter the tube.

While I have shown two burners in the drawings, it is to be understood that one burner may be employed or that a greater number 100

may be employed without departing from the spirit of my invention.

In operation when it is desired to fill the reservoir the plunger is to be drawn up and 5 the ring 14 engaged with the hook 15. After removing the plug 4 the filling-funnel 5 is to be placed in the nipple 3 and the valve 13 opened to permit the escape of air as the gasolene is poured in. After filling and after clos- 10 ing the valve 13 the ring 14 is to be released from the hook 15, so that the plunger will bear upon the gasolene. After a short preliminary heating by an alcohol-torch or the like held adjacent to the tube or tubes 22 gas 15 will be formed by the mixture of the gasolene and air in the thimble 24, and this formed gas will pass to the burner or burners.

It will be noted that a lamp embodying my invention is very simple in its construction, 20 and no parts are liable to get out of order, and the location of the weights 19 will indicate the amount of gasolene in the reservoir, or, in other words, will indicate when it is necessary to refill the reservoir. When it is necessary 25 to clean the reservoir, the cover and plunger may be easily removed.

Having thus described my invention, I claim as new and desire to secure by Letters Patent—

30 1. A gasolene-lamp, comprising a reservoir having guides projecting from its cover and provided with means by which it may be suspended, a plunger in the reservoir, a vent-tube secured to the plunger and extending out 35 through the cover of the reservoir, oppositely-projecting arms carried by the vent-tube, rods secured to the arms and passing through the guides and carrying weights at their ends, a generator-tube connected with the bottom of 40 the reservoir, and a burner-tube carried by the reservoir and into which discharges the generator-tube, as set forth.

2. A gasolene-lamp, comprising a reservoir, 45 means for suspending the reservoir, a plunger in the reservoir, a vent-tube secured to and extending upwardly from the plunger and beyond the upper end of the reservoir, oppositely-projecting arms carried by the vent-tube, weighted rods secured to said arms, a 50 generator-tube connected with the bottom of the reservoir, and a burner-tube carried by the reservoir and into which discharges the generator-tube, as set forth.

3. A gasolene-lamp, comprising a reservoir,

means for suspending the reservoir, a plunger 55 in the reservoir, a weighted vent-tube secured to the plunger and extending loosely through the cover of the reservoir, a supply-tube leading from the bottom of the reservoir and provided with lateral branches, inwardly-curved 60 generator-tubes on the ends of the said branches, and curved burner-tubes supported from the reservoir below the branch supply-tubes, each burner-tube supporting a burner and having a funnel-shaped end arranged op- 65 posite the generator-tube, as set forth.

4. A gasolene-lamp, comprising a suspended reservoir, a concavo-convex rubber plunger in the reservoir, a valved vent-tube secured to the plunger and extending loosely through the 70 cover of the reservoir and provided with oppositely-projecting arms, rods secured to the ends of the arms and carrying weights at their ends, a generator-tube connected with the bottom of the reservoir, and a burner-tube carried by the reservoir and into which the generator-tube discharges, as set forth.

5. In a gasolene-lamp a bent generator-tube, a metal netting arranged in the bend of the tube, and metal rods arranged in the upper 80 and lower portions of the tube and having connections with the opposite ends of the netting, substantially as specified.

6. In a lamp, the combination with a reservoir, 85 of a plunger therein, a vent-tube secured to the plunger and extending out through the cover thereof, opposite-projecting arms on the vent-tube, and rods secured to the ends of the arms and provided with weights at their ends, 90 as set forth.

7. In a lamp, the combination with a reservoir provided with apertured guide-arms projecting from its top and means for suspending the reservoir, of a plunger in the reservoir, a valved vent-tube secured to the plunger and projecting out through the cover of the reservoir, a cross-head secured to the vent-tubes, depending rods secured to the ends of the cross-head and passing through the apertures of the guide-arms, and weights on the 95 lower ends of said rods, as set forth.

In testimony whereof I have signed my name to this specification in the presence of two subscribing witnesses.

RICHARD PAUL HABEL.
